Primary Examiner — Mehri F Bajoul

(57) **CLAIM**

The ornamental design for an interactive simulator for video games as shown and described.

DESCRIPTION

The patent or application file contains at least one drawing executed in color. Copies of this patent or patent application publication with color drawing(s) will be provided by the Office upon request and payment of the necessary fee.

Fig. 1.1 shows a perspective view.

Fig. 1.2 shows a front view.

Fig. 1.3 shows a rear view.

Fig. 1.4 shows a left side view.

Fig. 1.5 shows a right side view.

Fig. 1.6 shows a top view.

Fig. 1.7 shows a bottom view.

Fig. 1.8 shows a further right perspective view.

Fig. 1.9 shows a rear perspective view.

Fig. 1.10 shows a further rear perspective view.
